F. F. WITKUS

TIP PERFORATING MACHINE

Filed Jan. 12, 1923

UNITED STATES PATENT OFFICE.

FRANK F. WITKUS, OF NEWPORT, NEW HAMPSHIRE.

TIP-PERFORATING MACHINE.

Application filed January 12, 1923. Serial No. 612,300.

To all whom it may concern:

Be it known that I, FRANK F. WITKUS, a citizen of the United States, a resident of Newport, in the State of New Hampshire 5 and Sullivan County, have invented an Improvement in Tip-Perforating Machines, of which the following is a specification.

This invention relates to machines for forming a series of small perforations in 10 sheet material, particularly in the tips and other leather portions of the upper of a shoe, for ornamental purposes.

Prior to my invention, machines for this purpose, which are in practical use have 15 consisted of a series of tubular punches which are variously arranged according to the design of figure to be punched, and mounted in a plate adapted to be removably arranged in a machine which comprises a 20 table for supporting the plate and a vertically movable head which is engaged with the plate to force the punching tubes through the leather which is placed in position therebeneath. Machines of this type 25 are objectionable for several reasons, principally because the punching tubes are expensive to manufacture and frequently become broken, and this difficulty is increased when perforations of particularly small diameter are required, also, in order that the 30 punching tubes may make a clean cut and entirely remove the material to be cut out, it is usually necessary to provide paper and soft metal for the tubes to cut against, and 35 if paper is employed, the cost thereof is a substantial item, while soft metal, when employed, dulls the cutting edges to an objectionable extent.

The objects of my invention are to provide a form of punching die adapted for use 40 in the machines now employed for tip-perforating, in which a solid punching tool, or punch rod, making a shearing cut, may be employed, and particularly to provide 45 means whereby punching devices of this character may be effectively employed for the above described purpose, so that the expense of construction may be reduced and the durability increased to an extent which 50 will make repairs unnecessary for long periods. Other objects are to provide a construction which will lend itself readily to an arrangement of the punches to form in any desired design, and to permit the formation of perforations of as small, or as 55 large diameter as may be desired.

I accomplish these objects by means of the construction hereinafter described and illustrated in the accompanying drawing in which:

Fig. 1 is a front elevation, illustrating a preferred embodiment of my invention.

Fig. 2 is a sectional view at line *a—a* of Fig. 1.

Fig. 3 is a sectional view at line *b—b* of Fig. 2.

Figs. 4 and 5 are views similar to Fig. 3, showing the parts in different position.

Fig. 6 is a top plan view.

Fig. 7 is an end view of the device and

Fig. 8 is a detail view of one of the punching tools.

It will be understood that the die embodying my invention is adapted for use in the same type of machine as that now generally employed for tip-perforating, said machine comprising, as indicated in the drawing, a table or support 1, on which the die, as a whole, is removably mounted, and a vertically movable head or plate 2, which is provided with means for causing the same to make a single reciprocation, upon the depression of a treadle.

According to my invention, I provide a die, which comprises a bed-plate 4, of oblong form, having a row of perforations 4^a, therethrough, which conform to the row of perforations which are usually formed in the rear edge portion of an ordinary shoe tip, and also with a series or cluster 4^b of perforations, arranged in some conventional design, to conform to the desired arrangement of perforations in the middle portion of the tip. A clamping or hold-down plate 6, of the same shape as the plate 4, is provided, having a series of perforations corresponding to the perforations 4^a and 4^b, and slidably mounted on a series of guiding posts 7, one being preferably arranged in each corner portion of the plate and the plate being held in such a position that its perforations exactly register with the perforations of plate 4. Each post 7 is provided with a shoulder 8, which engages the under side of the plate 6, and also with a tubular portion 9 which extends through the plate 4 and is slidably fitted in a bushing 10, supported in the plate 4 by a flange 11 at its upper end, the flange being flush with the upper surface 110 of the plate 4. A coiled lifting spring 12 is arranged in each tubular portion 9, and in

2

the bushing 10, between the inner end thereof and an adjusting screw 14, threaded in the lower end of the bushing 10. A head plate 16 is mounted on the upper end portions of the posts 7, and a screw 18 is threaded in the upper end of each post, the head thereof engaging the plate 16 and being countersunk, so that its outer surface is flush with the upper surface of plate 16. A coiled spring 20 is provided on each post 7 between the plates 6 and 16, the strength of which is substantially greater than that of each corresponding spring 12. The plate 16 is also provided with a series of perforations corresponding to the perforations 4^a, 4^b of plate 4, and which are held in register therewith and a corresponding series, or gang of punching tools or rods 22 are arranged in, and closely fitted in the perforations of the plate 16, each rod being bent over at its upper end to form a supporting head 22^a, which engages the upper side of plate 16, and extending into the perforations of the clamping plate 6. A back or top plate 24 is attached by screws 25 to the plate 16, so that it is held in close contact therewith, thereby providing an abutment for the headed ends of the punching rods 22 and also the heads of the screws 18. To provide an additional yielding engaging means between the plates 6 and 16, the plate 6 is recessed from its upper side to receive the lower ends of a pair of coiled springs 28, said springs extending through holes formed therefor in plate 16 and engaging the plate 24 at their upper ends.

A combined guiding and stop plate 30 is attached by screws 31 to each end of the plate 6, so that the adjacent surfaces of said plates 30 may slidably engage the end portions of the plates 4, 16 and 24, and said plates 30 are provided at their lower ends with inwardly projecting flanges 32 which, in the normal position of the parts, engage the under side of the plate 4 and limit the extent to which the plates 4 and 6 may be separated by the springs 12.

A series of gage pins 34 are mounted in the plates 6 and 16 similarly to the punch rods 22, and extend through corresponding apertures therein, and through the plate 4, said pins being arranged to engage the edge of a shoe tip when inserted between the plates 4 and 6, to position the tip with relation to the punching tools. To permit adjustment of pins 34 with relation to the punches, additional rows of perforations are provided in the plates located at different distances from the perforations 4^a. A guard plate 36 is preferably attached to the front edge of the plate 6 and extends opposite the front edge of the plate 16.

The normal position of the die is illustrated in Figs. 1 and 3, in which position

the springs 12 support the plate 6 at a sufficient distance from the plate 4 to permit the tip to be perforated to be readily inserted therebetween. When the tip has thus been inserted, the machine is operated to force the plunger 2 downward, causing downward pressure to be exerted on the surface of the top plate 24. As the combined strength of the springs 20 and 28 is made greater than the combined strength of the lifting springs 12, the plates 6 and 16 will be forced down together compressing the springs 12 until the plate 6 is engaged with the material to be punched and is pressed thereagainst under the tension of the springs 20 and 28. The material will thus be firmly clamped between the plates 6 and 4, as shown in Fig. 4. As soon as the springs 20 and 28 begin to be compressed, on further downward movement of plate 16, the punch rods 22 will be forced completely through the plate 6 and through the material into perforations of the plate 4 to a sufficient extent to sever the punched-out material completely from the sheet, as shown in Fig. 5, waste material, which is removed in the successive operations, being forced down through the perforations therein. When the plunger 2 is raised, the plates 6 and 16 will be lifted in the reverse order by the springs, the plate 6 then acting to strip the material from the punches. As the material will be firmly clamped at all points about each perforation in the base plate 4, each punch rod will have a perfect shearing action with the edges thereof, so that the material will be cut as smoothly as it would be with a sharp tubular punch.

If, for any reason, it becomes necessary to renew any of the punching rods, this may be readily done by removing the top plate 24 and removing the defective rods and inserting others, and if it is desired to perforate the edge-portion of the tip only, the rods which form the conventional figure may be removed.

I claim:

1. A perforating die comprising a bed plate, a clamping plate and a head plate disposed thereover, one above the other in parallel relation thereto, each plate having a series of perforations therethrough in registering relation, a series of guide posts connected to said head plate and extending through and slidably in said clamping and base plates, said posts having stop shoulders for engaging the under sides of said clamping plate to limit its movement from said head plate, clamping springs interposed between said head and clamping plates and normally holding said clamping plate against said shoulders, adjusting screws connected to said bed plate, lifting springs interposed between said screws and the

lower ends of said guide posts, means to limit the extent of separation of said base and clamping plate by said lifting springs and punch rods mounted in the perforations of said head plate and extending into the perforations of said clamping plates.

2. A perforating die comprising a bed plate, a clamping plate and a head plate disposed thereover, one above the other in parallel relation thereto, each plate having a series of perforations therethrough in registering relation, a series of guide posts connected to said head plate and extending through and slidably in said clamping and base plates, said posts having stop shoulders arranged to be engaged by said clamping plate to limit its movement from said head

plate, clamping springs interposed between said head and clamping plates and normally holding said clamping plate against said shoulders, bushings supported in said bed plate and within which said guide posts are slidably fitted at their lower ends, adjusting screws in the lower ends of said bushings, lifting springs in said bushings and engaged with said screws and with the lower ends of guide posts and stop devices connected to said clamping plate and arranged to engage said base plate to limit the separation thereof by said lifting springs.

In testimony whereof, I have signed my name to this specification.

FRANK F. WITKUS.
